COPYING MACHINE

Motoaki Sakamoto and Hisao Uchino, Tokyo, Japan,
assignors to Hitachi, Ltd.

Filed July 6, 1973, Ser. No. 377,023

Claims priority, application Japan Jan. 24, 1973

Term of patent 14 years

Int. Cl. D16—03

U.S. Cl. D61—1 Q

FIG. 1

FIG. 2

FIG. 3

FIG. 4

FIG. 5

FIG. 1 is a front, top and right side perspective view of a copying machine, showing our new design with the copy cover in closed position.

FIG. 2 is a front, top and right side perspective view of the copying machine shown in FIG. 1 with the copy cover in opened position.

FIG. 3 is a front elevational view of the copying machine shown in the position of FIG. 1.

FIG. 4 is a left side elevational view of the copying machine in the position of FIG. 1, and

FIG. 5 is a rear elevational view of the copying machine in the position of FIG. 1.

We claim:
The ornamental design for a copying machine, as shown and described.
